UNITED STATES PATENT OFFICE.

WILLIAM WALLACE KEMP AND WILLIAM H. VAN HORN, OF BALTIMORE, MARYLAND.

METHOD OF HEATING.

1,244,864.

Specification of Letters Patent. Patented Oct. 30, 1917.

Original application filed June 23, 1916, Serial No. 105,526. Divided and this application filed August 18, 1916. Serial No. 115,232.

To all whom it may concern:

Be it known that we, WILLIAM WALLACE KEMP and WILLIAM H. VAN HORN, citizens of the United States, residing at Baltimore, in the county of Baltimore City and State of Maryland, have invented new and useful Improvements in Methods of Heating, of which the following is a specification.

This invention relates to heaters, and more particularly to the method of heating carried out therein, and has as its object to provide a method of heating wherein a blast flame is utilized to create and maintain the circulation of a heated gaseous medium through a passage, the heated medium being repeatedly returned to the flame or blast to be heated thereby.

By returning the gaseous medium or products of combustion to the flame and repeatedly heating them in accordance with our improved method, a great economy in the consumption of fuel is obtained, for after passing through the passage, the combustion products still possess considerable heat, and less fuel is required to heat them to the desired temperature than if fresh atmospheric air were used. The heated gases or products of combustion are caused to circulate rapidly through the device employed in carrying out our improved method, the heat distribution is uniform, and the temperature produced may be easily and perfectly controlled, while, at the same time, the discharge of the products of combustion and dust into a chamber which it may be desired to heat is avoided.

This application is a division of our application for Letters Patent filed the twenty-third day of June, 1916, Serial No. 105,526.

In the accompanying drawings, we have illustrated an apparatus suitable for carrying the invention into practical use, and a description of our method of heating and utilizing the illustrated apparatus which will be sufficiently descriptive of such process when other apparatus is employed for carrying the same into use.

In said drawings,—

Figure 1 is an elevational view of the apparatus, a portion of the heater being broken away to disclose the burner.

Fig. 2 is a view similar to Fig. 1, showing a slightly different construction.

Referring to the drawings, wherein like numerals represent like parts in the several views, we have shown, in the present in-

stance, our improved method of heating as carried out in a heater comprising a radiator, but, of course, the method of heating herein described may be utilized in apparatus other than radiators. 10 designates a radiating pipe which is endless in that it forms a continuous passage through which the heated products of combustion are adapted to circulate. The radiating pipe may be 65 of any suitable construction, and may be constructed of wrought iron or any other suitable material.

Mounted within the radiating pipe is a burner tube 11 retained centrally within the 70 pipe by means of brackets or spiders 12. The burner tube 11 is mounted preferably at one of the angles or elbows of the radiating pipe with its inner end extending longitudinally into the inlet portion 13 of the radiating 75 pipe and its outer end projecting into the elbow, the latter end being in alinement with the through opening in the return portion 14 of the radiating pipe. Extending through an opening 15 in the wall of the 80 radiating pipe, and in alinement with the tube 11 is a gas pipe 16 carrying on its inner end a burner 17 which may be of any suitable construction.

The pipe 16 leads from a suitable air and 85 gas mixing device, and while any such suitable device may be employed, we prefer to connect the pipe 16 to a gas and air mixing apparatus of the general type disclosed in Patent No. 1,141,466, dated June 1, 1915, 90 granted to W. H. Van Horn and Wm. W. Kemp. In the device described in the last-mentioned patent, air and gas are mixed in such proportions, that the mixture is flame-sustaining; that is, sufficient oxygen is 95 in the mixture to completely burn the gas mixed therewith and no outside supporter of combustion is required. The pipe 16 has a regulating and shut-off cock 17' which may be of any desired form, and which has an 100 operating handle 18 provided with a pointer 19 which is adapted to move over an indicating scale upon the plate or member 20 when the handle is turned.

In Fig. 2, we have shown a device similar 105 to that disclosed in Fig. 1, but in the embodiment of the invention the radiator is disclosed as mounted horizontally (although it may be mounted vertically) in a japanning oven, the japanning oven being conventionally shown by the casing 21. It is, of course, obvious that the method of heating

herein disclosed is applicable for use in a great variety of apparatus, and we have shown the same applied in Fig. 2 to a japanning oven by way of illustration only. 5 In such oven, it is particularly desirable to eliminate introduction of products of combustion or dust into the space in which the articles to be japanned are located, to obtain a relatively high heat and to heat the oven uniformly, and with the use of our device, these requisites are obtained.

In Fig. 2, the radiator is shown as provided with a neck portion 22 extending through an opening in the wall of the japanning oven and having a chamber 23 with which the ends of the radiating pipes 10 are in communication, and by this construction, the exhaust gases may be discharged through the opening 15 about the pipe 16 into the atmosphere and thus introduction of these exhaust gases into the oven is eliminated. The tube 11 is so mounted that its outlet end lies within the inlet portion 13 of the radiating pipe and its inlet end lies within the chamber 23.

When it is desired to place the device disclosed in the drawings in operation, the handle 18 is turned (the amount to which it is turned being indicated by the position of 30 the pointer over the scale), to admit the air and gas mixture from its source (not shown) to the burner where it is ignited. The mixture of air and gas produces a flame which is self-sustaining, and the mixture is projected into the tube 11 with considerable pressure, thereby causing the products of combustion to travel through the tube 11 with considerable velocity. A strong suction is thus created about the burner which 35 draws or entrains atmospheric air into the tube 11 and about the burner. The products of combustion together with the entrained air are discharged from the outlet end of the tube 11 into the pipe 10 and the same circulate through the pipe 10 with considerable rapidity.

Immediately after starting the burner, an influx of air through the opening 15 is noticeable, and then for a short period of 50 time a noticeable exit of air through the opening 15 may be observed, this exit of air being due to the fact that the products of combustion from the burner forces or scavenges the pipe of the air with which the 55 same is filled when not in operation. After the device is in operation a short time, the products of combustion are repeatedly circulated through the radiating pipe, a portion of the products of combustion after 60 passing through the return portion 14 of pipe 10 being entrained or drawn into the pipe 11 about the burner 17 and a secondary suction being created in the space between the tube 11 and the surrounding wall of the 65 radiating pipe 10 due to the blast discharge

of the products of combustion from the outlet end of tube 11. During the normal operation of the device, a discharge of the excess combustion products through the opening 15 takes place, this being due, of course, 70 to the fact that a gaseous mixture is continuously admitted into the heater through the burner 17.

It will be noted that during the normal operation of the device, air or other gas is 75 not admitted to the radiator except through the burner 17, the gaseous mixture admitted to the burner being in such proportion that the flame is self-supporting. The discharge of combustion products from the 80 burner is such as to force the gaseous medium within the pipe 10 before them, and, at the same time, a suction action is created about the burner and about the tube 11 which draws the gaseous products of combustion passing through the return portion 85 14 into the inlet portion 13 of the radiator. These gases are again and again circulated through the radiating pipe and the circulation throughout the entire length of the radiator 90 pipe is very rapid, so that the heat is uniformly distributed. In place of discharging the products of combustion from the pipe after completing the circuit and drawing in fresh air, the products of combustion are again heated by the hot blast 95 from the burner and as the combustion products retain some of their heat, it requires less fuel to heat them to any given degree than if outside air were utilized.

When a radiator, in which our method of heating is employed, is applied to a japanning or other oven, the neck portion 22 preferably extends through an opening in the wall of the oven, so that excess products of 105 combustion discharged from the radiator pass off into the atmosphere and none of the products of combustion enter into the compartment in which the articles are treated, and thus dust and the like due to the burning of fuel, or dust which might be introduced due to draft currents, or stirred up thereby, are entirely eliminated. It is, of course, obvious that the neck portion 22 may be extended to any desired distance outside 110 of the oven 21 so that the burner 17 is sufficiently removed from the oven and this feature is particularly desirable from the fire insurance standpoint.

Our invention is susceptible of various 120 modifications and changes which would be within the spirit of the invention without departing from the scope of the following claims.

What is claimed is:—
1. The method of heating herein described, which consists in discharging at relatively high pressure an ignited flame-sustaining mixture into an endless passage from which air is excluded, entraining the 130

products of combustion, causing the circulation thereof within said passage at relatively high velocity, repeatedly heating said products of combustion, and discharging the products of combustion from said passage.

2. The method of heating a chamber which consists in discharging a flame under relatively high pressure forwardly into an endless pipe mounted in said chamber and from which pipe air is excluded, causing circulation of the products of combustion therein at relatively high velocity, and discharging the products of combustion from said endless pipe.

3. The method of heating herein described which consists in discharging at a pressure greater than that of the atmosphere an ignited flame-sustaining mixture into a substantially closed circuit having an exit at its return side, said mixture being discharged into said circuit in a direction to cause the products of combustion to flow around the circuit, and discharging the products of combustion from said circuit through said exit.

4. The method of heating herein described which consists in discharging at a pressure relatively higher than that of the atmosphere a flame into a substantially closed endless pipe from which air is excluded and having an exit at its return side, said flame being discharged into said pipe in a direction to cause the products of combustion to repeatedly circulate within the pipe at relative high velocity, and discharging the products of combustion from the pipe through said exit.

5. The method of heating a chamber which consists in discharging under pressure greater than that of the atmosphere an ignited flame sustaining mixture into a substantially closed circuit mounted within the chamber and having an exit at its return

side, said mixture being discharged into the circuit in a direction to cause the products of combustion to flow around the circuit, repeatedly circulating and heating said products of combustion, and discharging the products of combustion from the circuit through said exit.

6. The method of heating herein described, which consists in discharging under pressure greater than that of the atmosphere an ignited flame sustaining mixture into a tube mounted within an endless substantially closed circuit from which air is excluded and having an exit, said mixture being discharged into said tube in a direction to cause the products of combustion to flow around the circuit, entraining the products of combustion within the tube and within the space about the same, and discharging the products of combustion from said circuit through said exit.

7. The method of heating herein described, which consists in discharging an ignited flame sustaining mixture forwardly at a pressure greater than that of the atmosphere into a tube mounted within a substantially closed pipe from which air is excluded, and which pipe has an exit opening at its return side, entraining the products of combustion within the tube and within the space about the same, causing circulation of the products of combustion at relatively high velocity within the pipe, and discharging the products of combustion through the exit opening of the pipe.

In testimony whereof we have hereunto set our hands in presence of two subscribing witnesses.
